UNITED STATES PATENT OFFICE

OSCAR CHARLES ROESEN, OF BROOKLYN, NEW YORK, ASSIGNOR TO WOOD NEWSPAPER MACHINERY CORPORATION, OF NEW YORK, N. Y., A CORPORATION OF VIRGINIA

MATRIX ROASTER

Application filed September 2, 1926, Serial No. 133,161. Renewed June 17, 1931.

This invention relates to a device for roasting stereotype printing plate matrices. The principal objects of the invention are to provide a machine which can operate continuously and in which the matrices can be introduced at one point and withdrawn at another, fully and uniformly dried and roasted; to provide a construction in which the speed of operation can be varied to subject the matrices to the heat longer or shorter periods of time as may be found necessary; and to provide a construction in which the introduction and withdrawal of the matrices is a simple and convenient matter.

Other objects and advantages of the invention will appear hereinafter.

Reference is to be had to the accompanying drawings in which

Fig. 1 is a plan of a matrix roaster constructed in accordance with this invention; and

Fig. 2 is a side view of the same partly in section.

The devices which have been used heretofore for roasting stereotype matrices have been of the type to operate by hand and to roast the matrices individually, with no means for accomplishing any of the above mentioned results. The matrix is left in as long as the operator may judge necessary and the result is a wide range in the amount of moisture left in the matrix after roasting. Also the work is done very slowly and one of the operators has to attend to each matrix individually and has to wait for one to be entirely dried before starting another.

In order to avoid the delay and uncertainty, and to accomplish the results above mentioned, I provide a roaster in the form of a drum 10 mounted on a stationary vertical spindle 11 and rotatable about that spindle as an axis. The method of rotation is shown as comprising a motor 12 having a driving wheel 14 which can be adjusted longitudinally along a driven disc 15, the surface of which it engages. Obviously the speed of rotation of the disc is controlled by the position of the wheel 14 and the speed of the machine is easily controlled. This wheel 15 is mounted on a shaft 16 which, by a worm 17, drives

a worm wheel 18 rotatably mounted on the shaft 11. The shaft is mounted on a base 19 which carries a bearing 20 adjusted by screws 21.

Underneath the drum, extending part way around it, are a series of gas pipes terminating in burners 22 for heating the drum underneath. This drum is formed with a flat bottom and cylindrical side rotatable about the shaft. A top 23 is secured in position to rotate with the drum and a hub 24 at the top of the spindle 11.

The drum is provided with a series of curved walls forming pockets 25 between them of a shape corresponding with the curve of a matrix. These pockets or compartments are adapted to receive one matrix M each and hold it in curved position while being dried.

It will be noted that the matrices M stand up on edge in the pockets 25 and that these pockets are closed by end walls which constitute part of a cylinder. Each matrix is introduced into one of the pockets through a correspondingly curved slot 26 in the top 23 and removed therethrough after a rotation. The walls of the pockets 25 are provided with hand holes 28 on both sides and the slots 26 are provided with similar hand holes 29 so that the operative can introduce and remove the matrices conveniently by the fingers.

The gas burners may extend throughout substantially the entire bottom of the drum except where a space is needed for the motor or the wheel 15. It will be obvious that the speed of rotation having been fixed by proper adjustment of the wheel 14, rotation will be constant. Thus each matrix will be in the roaster the same length of time and thus be subjected to the same amount of heat.

In this way the roasting is uniform. A few matrices can be tested to see if they are dry enough and then the adjustment made to secure the desired results. In this way a uniform product can be secured and one operative can handle as many matrices as a large number could under the old conditions. Also only one machine is required occupying only very little space to do the work of a large

number of the old form of matrix roasters.

The results above mentioned are thus obtained. The matrices can not get out of shape and they are roasted uniformly.

6 Although I have illustrated and described only two forms of the invention, I am aware of the fact that modifications can be made therein by any person skilled in the art without departing from the scope of the invention
10 as expressed in the claims. Therefore, I do not wish to be limited to all the details of construction herein shown and described but what I do claim is:—

15 1. A matrix roaster comprising a drum rotatable on a vertical central axis and having a series of curved pockets, each extending from a point near the center to a point near the circumference adapted to receive matrices therein standing on edge and to hold
20 the matrices in curved formation, and means for applying heat to the bottom of the drum as it rotates.

25 2. In a matrix roaster, the combination with a drum having pockets therein arranged to extend from a point near to the center to a point near the edge and rotatable on a central axis, of means for applying heat to the drum to dry the matrices, said drum having a cover provided with slots adapted to register with each pocket, whereby matrices can be introduced and withdrawn.

30 3. In a matrix roaster, the combination with a drum having pockets therein on a vertical axis, of means for applying heat to the drum to dry the matrices, said drum having a cover provided with slots of the same shape as said pockets and registering with them, whereby matrices can be introduced to enter the pockets at one point and withdrawn at another after they have passed far enough around to be dried.

35 4. In a matrix roaster, the combination with a rotatable drum having curved pockets therein, said drum having a cover provided with slots of the same shape as said pockets and adapted to register with them, whereby matrices can be introduced to enter the pockets and withdrawn, said cover and pockets having hand holes to aid in introducing and
40 removing the matrices by hand, of means for applying heat to the drum to dry the matrices uniformly.

45 In testimony whereof I have hereunto affixed my signature.

50 OSCAR CHARLES ROESEN.
